UNITED STATES PATENT OFFICE

146,765

DESIGN FOR A MIRROR FRAME OR THE LIKE

Frederic H. Fisher, Syracuse, N. Y., assignor to Syracuse Ornamental Co. Inc., Syracuse, N. Y., a corporation of New York

Application May 10, 1946, Serial No. 129,526

Term of patent 14 years

(Cl. D29—20)

To all whom it may concern:

Be it known that I, Frederic H. Fisher, a citizen of the United States, residing in Syracuse, in the county of Onondaga and State of New York, have invented a new, original, and ornamental Design for a Mirror Frame or the like, of which the following is a specification, reference being had to the accompanying drawing, forming a part thereof.

Fig. 1 is a front view of a mirror frame or the like showing my new design; and

Fig. 2 is a side perspective view thereof.

I claim:

The ornamental design for a mirror frame or the like, substantially as shown.

FREDERIC H. FISHER.
